UNITED STATES PATENT OFFICE.

HERMAN M. BREKKE, OF VIRGINIA, MINNESOTA.

CLOTHESPIN CARRIER.

Application filed November 13, 1923. Serial No. 674,524.

To all whom it may concern:

Be it known that I, HERMAN M. BREKKE, citizen of the United States, residing at Virginia, in the county of St. Louis and State 5 of Minnesota, have invented certain new and useful Improvements in Clothespin Carriers, of which the following is a specification.

This invention relates to a carrier or bag 10 particularly adapted for the reception of clothes pins, the primary object of such an invention being the provision of an article that includes a member to which a piece of cloth or other suitable fabric may be so attached as to provide a bag for the reception 15 of clothes pins, the means to which said piece of cloth or other fabric is secured being provided with a means whereby the same may be detachably engaged with the 20 clothes line, and this in such a manner that the bag or carrier may be moved along the clothes line during the hanging of clothes for providing a ready means for obtaining 25 clothes pins during the clothes hanging operation.

One of the main objects of this invention resides in the provision of an article of this character that may be manufactured and marketed at an extremely small cost, the 30 device being very simple of construction, the same comprising essentially but two parts that may be detached, but operatively joined together in a simple and quick manner.

With the above and other objects in view 35 as the nature of the invention will be better understood, the same comprises the novel form, combination and arrangement of parts hereinafter more fully described, 40 shown in the accompanying drawings, and claimed.

In the drawings, wherein there is shown the most practical embodiments of the present invention, and wherein like reference 45 characters designate corresponding parts throughout the different views:

Figure 1 is an elevational view of a clothes pin carrier constructed in accordance with the present invention, the same 50 being shown in use.

Figure 2 is an elevational view of one of the main elements comprising the present invention, said main elements including an

angular shaped metal plate provided at its corners with clasp members for allowing 55 the detachable engagement of the before-mentioned piece of cloth or suitable fabric, said plate member having associated therewith a hook element for allowing the assembled carrier to be positioned upon a clothes 60 line and to be readily removed in opposite directions thereon.

Figure 3 is a plan view of said plate member,

Figure 4 is a plan view of the blank from 65 which this member is formed, and

Figure 5 is a similar view of the before-mentioned cloth elements that is adapted 70 to be detachably associated with said plate member.

Now having particular reference to the drawings, my novel clothes pin carrier embodies the provision of a relatively squared sheet metal plate 5 that is formed at its four corners with relatively narrow tongues 75 6, and at its center point with a small opening 7 for the reception of the lower end of the shank portion of a suitable hook 8.

In the formation of the cloth element attaching member, said square shaped plate 5 80 is bent downwardly at its different corners upon the fold lines 9, after which the before-mentioned tongues 6 may be reversely bent for providing spring clasps 10.

The clothes pin receiving element per se 85 embodies as shown in Figure 5 a substantially square shaped piece of fabric 11, the edges of which are suitably reinforced as at 12 and the four corners of which are formed with eyelet reinforced openings 13 it being 90 of course understood that in actual use, this cloth may be detachably associated with the plate 5 by engaging said opening 13 over the clasp 10 at the opposite corners 95 of said plate.

It will thus be seen that I have provided a highly novel and useful form of clothes pin carrier and one that may be readily supported upon the clothes line and moved to the desired position thereon during the clothes hanging operation for allowing ready access to be had to the clothes pin.

Although I have herein shown and described, the most preferred embodiments of the present invention, with which I am at 100 this time familiar, it is nevertheless to be 105

understood that minor changes may be made therein without departing from the spirit and scope of the appended claim.

Having thus described my invention, what I claim as new and desire to secure by Letters Patent is:

In a clothes pin carrier of the class described, a plate element, attachment members formed at the corners of said plate

member, a strip of cloth of relatively greater dimension than said plate member and formed at its corners with openings for engagement with said attachment members at the corners of said plate.

In testimony whereof I affix my signature.

HERMAN M. BREKKE.
